FREDERICK VOLKMAN, OF HOBOKEN, NEW JERSEY.

Letters Patent No. 65,709, dated June 11, 1867.

PLOUGH.

The Schedule referred to in these Letters Patent and making part of the same.

TO ALL WHOM IT MAY CONCERN:

Be it known that I, FREDERICK VOLKMAN, of Hoboken, Hudson county, New Jersey, have invented a new and improved Plough; and I do hereby declare that the following is a full, clear, and exact description thereof, which will enable others skilled in the art to make and use the same, reference being had to the accompanying drawings, forming part of this specification, in which—

Figure 1 represents a front elevation of my improved plough.

Figure 2 is a side elevation of the same.

Figure 3 is a plan or top view of the same.

Figure 4 is a detail side view of a portion of the plough-beam.

Figure 5 is a plan or top view of the same; and

Figure 6 is a vertical cross-section of the same, taken on the line $z z$, fig. 4.

Similar letters of reference indicate corresponding parts.

This invention relates to certain improvements on the plough for which Letters Patent were issued to me on the twenty-seventh day of November, 1866.

The improvement consists, first, in so securing the lower end of the upright screw-shaft, to which the front end of the plough-beam is secured, in the axle of the plough-cart that the upper frame and sliding block for sustaining the upper part of the said screw-shaft may be dispensed with; second, in making the axle of one solid piece, not weakening it by slots, as in the original patent, and bending the draught-bar so that it will pass under the axle and not through the same; third, in making the attachment of the draught-chain to the plough-beam laterally adjustable, so that it can be regulated in conformity with the wearing of the ploughshare.

A represents the axle of the plough-cart. B is the large wheel, and C the small wheel. Both of the latter are hung to the axle in the ordinary manner, but if desired the small wheel can be secured to an adjustable L-shaped bar, as described in the aforesaid Letters Patent. The axle is made of one solid bar of iron, or other suitable material, and is provided with round or other vertical holes $a a$ to receive the lower end of the screw-shaft D, which passes entirely through the axle, projecting below the same, as shown. A clamp, E, is secured around the axle, so as to enclose the screw-shaft directly above and below the axle, and is provided with a set-screw, a' , which presses against the front of the axle. By means of this set-screw the screw-shaft can be so firmly clamped between the front of the axle and the rear of the clamp E that it will be immovable, and cannot be turned. A key, b, can be passed through the shaft D below the axle A, as shown in fig. 1, for the purpose of preventing the said shaft from being raised out of the axle, while a shoulder is formed on the screw, by which it rests upon the clamp E or axle A. When the screw is to be adjusted on the axle the key b must be removed, and the screw can then be set into any one of the holes in the axle, and secured therein, the clamp being fitted around that portion of the axle through which the screw is to pass. c is the upper nut, which fits around the screw D, and to which the balance-beam d is pivoted, that is, connected by chains $e e$ with the front end of the plough-beam F. f is the lower nut or double nut, also surrounding the screw D, which nut is connected by the chain g with the left-hand side of the plough-beam F. The chain g is made adjustable by means of the set-screw h. All these parts, c, d, e, f, g, and h, are substantially like those described in the aforesaid Letters Patent. G is the draught-bar, which is pivoted to the under side of the axle A by means of a bolt, i, which passes through one of the holes in the axle A, and through the back part of the draught-bar. A key, j, is passed through the lower end of the bolt to sustain the draught-bar.

H is the semicircular perforated or notched plate, which is secured to the axle, and projects from the front of the same; and k is the set-screw, and l the clamp, by which the bar G is secured to the plate H. I is the draught-chain, which is connected with the draught-bar, in the manner shown in fig. 2, and of which the rear end is secured to a loop or link, J, that is secured to the plough-beam. This loop or link is made of strong wire or bar iron, and is bent so as to form the three sides of a square or oblong, as is clearly shown in figs. 4, 5, and 6. The side or end arms are pivoted to a bolt, m, which completes the square. The lower arm is provided at or near its left side with a downward bent projection, wherein the chain is held and confined. The bolt m passes through a box, K, which is secured on top of the plough-beam, and in which a set-screw, n, is arranged for holding and clamping the bolt m in any position.

By this device the end of the draught-chain is always held below the plough-beam; but it can be arranged nearer to or further from the land-side of the plough-beam by shifting the loop *J* *m* in the box *K*, and then securing it in the new position by the set-screw *n*. This arrangement is necessary, as the lower edge of the mould-board is worn off, and the plough will then be apt to lean in the direction in which the draught-chain tends to place it. It is therefore necessary to weaken in such a case the power of the chain, and remove it a little from the extreme left-hand side of the plough-beam.

Having thus described my invention, what I claim as new, and desire to secure by Letters Patent, is—

1. Securing the upright screw-shaft *D* in the axle *A*, in the manner set forth, and clamping it by means of a set-screw, *a'*, and clamp *E*, substantially as herein shown and described.
2. The link *J*, when arranged laterally adjustable on the plough-beam, substantially as herein shown and described, and for the purpose of changing the draught of the chain *I*.
3. The adjustable draught-bar *G*, when secured by a bolt, *i*, to the solid axle *A*, and when connected with the draught-chain *I*, substantially as set forth.
4. Securing the front end of the plough-beam to a vertical rod, *D*, which projects from the axle of a cart, substantially as herein shown and described, the said rod not being secured or supported in any frame or other device that is arranged above the axle *A* and in contact with the same, substantially as set forth, and for the purpose of making the whole cart lighter and of simpler construction.

F. VOLKMAN.
